EDWARD S. RITCHIE, OF BROOKLINE, MASSACHUSETTS.

Letters Patent No. 71,218, dated November 19, 1867.

IMPROVEMENT IN AIR-PUMPS.

The Schedule referred to in these Letters Patent and making part of the same.

TO ALL PERSONS TO WHOM THESE PRESENTS SHALL COME:

Be it known that I, EDWARD S. RITCHIE, of Brookline, in the county of Norfolk, and State of Massachusetts, have made a new and useful Invention having Reference to Air-Pumps; and do hereby declare the same to be fully described in the following specification, and represented in the accompanying drawing, which denotes a vertical section of an air-pump barrel and its piston, as provided with my invention.

In such drawing, A denotes the said barrel, B the piston-head, and C the stem or rod of such piston-head. This stem or rod extends into an air-duct, c, made axially within the head B, and terminating at its bottom in a conical valve-seat, a, within which is a conical valve, b, which, at its lesser base, is fixed to the lower end of the rod C.

A plate, d, provided with a series of holes, e, made through it, is fastened to the lower part of the piston-head B, by means of screws f, and serves as an abutment for the valve-head b to strike against, when the piston-rod is pressed down, so as to force the valve b off its seat a.

Sundry eduction passages g go through the upper head h of the barrel A, and open into a valve-box or dome, D, screwed into or fixed upon the top h, there being an escape pipe or passage, E, leading out of the head and from such dome.

In the lower head i of the barrel is a conical valve-seat, k, which communicates with a vertical and cylindrical passage, l, from which an induction pipe, m, extends. This latter pipe is to open communication between the barrel and the glass receiver of the air-pump.

A conical valve, o, provided with a prismatic extension or guide, n, is placed within the seat k. The said stem extends into the passage l, and serves to guide the valve in its vertical movements.

The rod q of the valve o extends through the piston-head B, and a stuffing-box, p, formed therein. At the lower end of the rod q is a cylindrical neck, r, having a diameter less than that of the rod, and going through a hole, s, in a plate, t, which is screwed to the upper surface of the valve. The hole has a diameter less than that of the rod, but greater than that of the neck, and such neck terminates in a head, u, having a diameter larger than that of the hole s. There is a chamber, v, made in the valve to receive the head u, and allow it to play laterally therein.

Furthermore, to the valve o, and so as to project from its upper edge, and over and beyond the seat of the valve, in manner as represented in the drawing, I affix a thin, annular flap-valve, w, of oiled silk, or its equivalent, whose purpose is to render certain the closing of the valve-seat k, when the valve o is depressed therein. It is a highly useful auxiliary to the said seat and its valve. The neck r, the hole s, and the head u, admit the valve o, to adjust itself laterally to its seat, however the rod q may become eccentric with reference to the seat of the valve.

Within a chamber, x, made in the upper head of the pump-barrel, and so as to open out of the same, is a lever, F, one of whose arms extends directly over the upper end of the valve-rod q. The tail or other arm of the said lever projects out of the chamber x a short distance, so that when the piston-head B is in the act of approaching the head h, such piston-head B may be carried against the tail of the lever, so as to cause such lever to be moved in a manner to press down the rod q, and force the valve o down upon its seat.

In this air-pump the valves o b are operated, not by the suction and pressure of the air, but automatically by mechanism applied to them. They will open and close, therefore, however attenuated the air may be in the vessel from which it is to be extracted. The instant the piston may be raised in the barrel, the friction of the stuffing-box on the valve-rod q will cause the valve o to be raised off its seat, and it will rise until the valve-rod may bring up against the lever F, and cause such to abut against the top of its chamber x. After this the piston-head, during its further elevation, will slide on the rod q. Just previous to the piston-head reaching the upper end of the barrel, it will come in contact with the tail of the lever F, and will move such lever, so as to effect the closing of the valve o, preparatory to the next descent of the piston. The piston-rod in descending will force the valve b off its seat a, so as to allow the air below the piston to pass through the valve-seat a, and the passage c, while the piston may be descending. Next, the piston-rod, by pressure against the cap-plate d, will drive the head B downward. During the upward stroke of the piston, the air contained in that part of the barrel which is over the piston will be expelled through the passages g, over which and within the dome D is a

valve, w' , as represented in the drawing. Now, were there no lever F, or its equivalent, to operate the valve-rod q, during the ascent, and by means of the piston, the piston would have to descend a short distance before it would effect the closing of the valve. Consequently, a small amount of air would be forced back through the lower valve-seat before closure of the valve would take place. This would prevent a thorough extraction of the air from the receiver of the air-pump, but, by means of the lever F, the closure of the valve o is effected while the piston is just at or in close proximity with the terminus of its upward stroke, and before the opening of the valve b.

From the above it will be seen that I have combined with the barrel, the piston, and the piston and induction valves and their seats, mechanism for automatically operating, or opening and closing both the said valves, independently of the elastic force of the air. It is not new to so operate the piston-valve, but it is new, as I believe, to so actuate both the valves, and especially the induction-valve; the same enabling me to produce a much higher degree of attenuation or extraction of air from the receiver of the air-pump than has heretofore been obtained.

I therefore claim as my invention the following; that is to say—

I claim the combination as well as the arrangement of the lever F, the rod q, and the stuffing-box p, with the valve o, the piston B, and the barrel A.

I also claim the application of the valve-rod q to the valve o, so as to be movable laterally relatively thereto, in manner substantially as and for the purpose described.

I also claim the combination and arrangement of the annular flap or auxiliary valve w, with the valve o and its seat k.

I also claim the combination of the prismatic guide n, or its equivalent, with the valve o and the passage l, and with the rod q applied to the valve o, so as to be movable laterally therein, or with respect to it, as specified.

E. S. RITCHIE.
